UNITED STATES PATENT OFFICE.

MAX L. HAAS, OF CLEVELAND, OHIO, ASSIGNOR TO THE HAAS ELECTRIC SALES COMPANY, OF CLEVELAND, OHIO.

DESIGN FOR AN ELECTRIC FIXTURE.

Application filed February 3, 1922. Serial No. 525. Term of patent $3\frac{1}{2}$ years.

To all whom it may concern:

Be it known that I, MAX L. HAAS, a citizen of the United States, residing at Cleveland, in the county of Cuyahoga and State of Ohio, and whose post-office address is 638 Huron Road, have invented a new, original, and ornamental Design for Electric Fixtures, of which the following is a specifica-

tion, reference being had to the accompanying drawing, forming part thereof.

The figure is a side elevation of my electric fixture, showing my new design.

What I claim as my invention is:

The ornamental design for an electric fixture, as shown.

MAX L. HAAS.
